(57) **CLAIM**

The ornamental design for a case for electronic communication device, as shown and described.

DESCRIPTION

FIG. 1 is a front, left, and top perspective view of a case for electronic communication device showing my new design; FIG. 2 is a rear, right, and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is an enlarged view of portion 9 shown in FIG. 1; FIG. 10 is an enlarged view of portion 10 shown in FIG. 2; FIG. 11 is an enlarged view of portion 11 shown in FIG. 3; and, FIG. 12 is an exploded front, left and top perspective view thereof.

The dashed broken lines in the drawings depict portions of the case for electronic communication device that form no part of the claimed design. The dot-dash broken lines in FIGS. 1, 2, 3, 9, 10, and 11 form no part of the claimed design; they delineate portions of the case for electronic communication device, including claimed subject matter, that are shown on an enlarged scale in FIGS. 9, 10, and 11.
